UNITED STATES PATENT OFFICE.

JAMES L. HARRIS AND MARGARET D. HARRIS, OF LINCOLN, NEBRASKA.

IN-A-WALL DINING CABINET.

Application filed October 6, 1925. Serial No. 60,839.

Our invention relates to the class of built-in furniture, especially of the kind having a dining table with benches which are foldable either against the wall or against the cupboards to conceal the cupboards. It is the object of our invention to provide an in-a-wall dining cabinet which may be built into the wall of either a new or old house, which will save space to thus give the equivalent of an additional room and which will materially reduce the labor of the home. Having in view these objects and others which will be mentioned in the following description, we will now refer to the drawings in which

Figure 1 is a front view in perspective of the entire in-a-wall dining cabinet showing the cabinet in open position and disclosing the shelving and other parts in the rear of the table and benches.

Figure 2 is a front perspective view of the in-a-wall dining cabinet as it appears when closed.

Figure 3 is a perspective view showing particularly the hinge connection between the bench and the cabinet.

Figure 4 is a perspective view of a fragmentary portion of the bench showing the hinge and the brace for the back of the bench.

Figure 5 is a sectional view of the rear portion of the table showing the connections with the cabinet.

Figure 6 is an inverted sectional view of a portion of the table with its leg and showing particularly the brace.

Our in-a-wall dining cabinet is a unitary structure and it is designed for factory production to be built in the walls of either a new or old house. It has a base 10, side walls 11, and a top 12 and it is also provided with a back wall which is not shown in the drawings. The base 10 is intended to rest on the floor of the room. Connecting the two sides 11 is a transverse partition 13 at a comfortable height for the benches. Between the base 10 and the partition 13 is a vertical partition 14 dividing the lower portion of the cabinet into two parts which are adapted to receive the drawers 15. Above the partition 13 is a panel 16 and above this is a projecting portion 17, the top edge of which is at a suitable height for the table.

The table is pivotally secured to the projecting portion of the partition 17 in the manner shown in Figure 5. A hinge, which may be of the form shown for the bench in Figure 4, connects the two together. At its rear the table 18 has a strap of suitable metal extending rearwardly and at its rear end the strap carries a coiled tension spring 19 which extends through apertures in the partitions 13 and 17 being secured at its lower extremity to an abutment 20. The spring 19 thus serves as a counterbalancing spring to prevent the table from falling suddenly and to facilitate the folding of the table. When unfolded the table rests on its hinge at its inner end and on the leg 21 supporting the outer portion. The leg 21 is hinged at its upper end to the table, and to maintain the leg in its upright position when the table is unfolded, there is provided an automatic brace and latch as shown in Figure 6. The brace 22 is hinged to a strap which is secured to the rear side of the leg 21. The underside of the table is provided with a groove which is covered by the member 23 having a groove therein for guiding the movement of the brace 22 and for preventing the brace from passing out through the groove. In the bottom of the groove is a resilient latch 24 which functions automatically when the leg is unfolded and which must be manually released when folding the leg. The leg is preferably provided with a mirror which is exposed both when the table is unfolded and when it is folded to give to the whole structure a very attractive appearance in addition to the utility of the mirror itself. The leg is supported on a pair of rubber feet 25 which prevent injury to the floor and obviate noise.

The two benches are of necessity secured to the cabinet at a lower level than the table. They are both hinged to the edge portion of the partition 13, which brings them when folded to the proper height. The benches are each made up of two parts, the seat 26 and the back 27 connected by a continuous hinge 28. This hinge has alternate leaves secured to the seat and back respectively, all of the leaves being connected by a single pin. This type of hinge obviates the necessity of forming grooves in the seat and back since the leaves will occupy a continuous plane when the bench

is in its upright position. For reinforcing the back 27 there is provided a plurality of brace straps 29 projecting beyond the edge of the back. The rear edge of the seat is 5 grooved out to receive the projecting ends of the straps 29 and the grooves thus formed are reinforced with suitable metal to prevent undue wear against the wood of the seat. The bench is hinged to the 10 cabinet as shown in Figure 3. The hinge employed is L-shaped, both portions serving as pivot pins. The vertical portion of the hinge 30 is set in a vertical sleeve 31 extending to the bottom of the cabinet. The 15 metal plate 32, which is T-shaped in form, has the double function of serving as a bearing for the vertical portion of the hinge 30 and for supporting the edge of the bench when the bench is folded. The horizontal 20 portion of the hinge passes through metal bearings which are positioned in a cutaway portion of the seat 26, the cut-away portion being covered with the metal strip 33. This construction gives access to the horizontal 25 portion of the hinge whenever it is desired to repair or adjust the parts. The walls 11 are notched at 34 as shown in Figure 2 to receive the backs of the benches. The 30 benches are also provided with legs 35 similar to the leg 21 of the table and have rubber feet 36, but no mirror. The L-shaped hinge construction for the benches permits movement of the benches into either of two positions as shown in Figure 35 1, and it also permits the folding of the table into the cabinet.

Since the benches are secured to the cabinet at a lower level than the hinge of the table, their upper ends when folded 40 will be lower than that of the table because the benches have substantially the same length as the table. We therefore secure two panels 37 in fixed position and provide releasable latches of any desired form at 45 the lower edges for engaging the outer or top edges of the benches. The space behind these panels 37 is the only space within the cabinet which is not fully utilized, but even a large portion of this space 50 is available for storage. Behind the lower portions of the benches there are two concealed drawers 38 which are ideal for the storage of silverware or papers. Above 55 these drawers is the partition 17 and the space above this partition is utilized for shelving. In our preferred form there are two vertical partitions 39 at the edges of the table dividing the space above the partition 17 into three cupboards. Each of 60 these cupboards has a sliding slat door. The door for the middle cupboard is moveable upwardly until it is entirely out of sight, so that the shelving above the table is available for chinaware and other table 65 ware. The sliding slat doors of the two

side cupboards are moveable sideways toward the outer sides of the cabinet and also moveable to concealed positions. One of these cupboards is preferably provided with a vertical partition to give space for 70 broom and dusters and the like. The inner portions of the outer cupboards are provided with shelving for the storage of kitchen or table ware or books as shown in Figure 1. Above the middle cupboard 75 there is a vacant space at 40 which is entirely covered by the table when it is folded. This space, however, is also available for storage and it is preferably provided with a pair of sliding doors for entirely closing 80 the space.

Our in-a-wall dining cabinet is adapted for use in all kinds of houses and most especially in apartment houses, summer homes, and in other buildings where the 85 living quarters are limited. In old buildings the front portion of the cabinet may project into the room, but in new buildings the exterior walls may be so formed as to accommodate the cabinet. In apartment houses particularly, where all of the 90 kitchens are arranged in tiers, it is possible to build a continuous outside wall so as to leave a space which will accommodate the cabinets in all the rooms of the tier. In 95 an old building if lack of space or other factors prevent the extension of the cabinet into the room, and it is not desired to alter the outside of the building, the cabinet portion may be omitted, leaving only the table 100 and benches.

Since all of the chinaware, silverware, and table linen are in the cabinet contiguous to the table it is possible to set the table from one position, with the fewest possible 105 number of steps. In fact, many of the kitchen utensils may be stored in the cabinet where they are of most convenient access. The table and benches together form a very attractive breakfast nook, but they are amply large for dining purposes. Each of the benches is long enough to support three persons and by placing two chairs at the end of the table, it is possible to accommodate eight persons at the table. The 110 table is an ideal card table or reading or writing table.

Having thus described our invention in such full, clear, and exact terms that its construction and utility will be readily understood by others skilled in the art to which it pertains, what we claim as new and desire to secure by Letters Patent of the United States is:

A built-in dining cabinet having a table and a pair of benches secured thereto, each of said benches being secured to said cabinet by an L-shaped hinge, a vertical tubular socket member in said cabinet for receiving one portion of said L-shaped hinge, a 125

metallic T-shaped abutment in said cabinet for supporting the edge of the bench when said bench is folded, said abutment being provided with an aperture in alignment with said socket member to serve as a bearing for said L-shaped hinge, the horizontal portion of said L-shaped hinge having a

bearing in the seat portion of the bench adjacent the end edge thereof.

In testimony whereof we affix our signatures.

MR. JAMES L. HARRIS.
